UNITED STATES PATENT OFFICE

2,502,413

SEAMING HEAD FOR CONTAINERS

Stellan Birkland, San Francisco, Calif., assignor
to American Can Company, New York, N. Y., a
corporation of New Jersey

Application May 17, 1948, Serial No. 27,400

6 Claims. (Cl. 113—24)

1

The present invention relates to seaming heads such as are used in the uniting of sheet metal covers or end members to containers or cans by an interfolding of flange parts thereof and has particular reference to an improved seaming head for rectangular, oval and other than round shaped containers or cans.

An object of the invention is the provision of an improved rotatable seaming head wherein the overall diametrical dimensions are greatly reduced over seaming heads currently and heretofore in use, without reducing or impairing strength and serviceability, so that closer can spacing may be used in the seaming machine in which the head is embodied, and the size of the machine as a whole and required floor space are reduced to a minimum.

Another object is the provision of such an improved seaming head wherein greater speed of rotation is obtained due to the decreased size of the head, with the result that greater production may be effected.

Another object is the provision of such an improved seaming head the initial cost and upkeep of which is very economical and wherein the arrangement of the head parts facilitates greater accuracy in the operation of the head and the forming of the end seam that unites the covers with the cans.

Another object is the provision of such a seaming head wherein each seaming unit includes a single rocker shaft which carries the seaming roller and which is rocked for the dual purpose of guiding the seaming roller around a chuck in an orbit parallel to the contour of the chuck and of shifting the seaming roller into and out of seaming position.

Numerous other objects and advantages of the invention will be apparent as it is better understood from the following description, which, taken in connection with the accompanying drawings, discloses a preferred embodiment thereof.

Referring to the drawings:

Figure 1 is a vertical section of a seaming head embodying the instant invention, with parts broken away;

Figs. 2, 3, 4, 5 are horizontal sections taken substantially along the respective lines 2—2, 3—3, 4—4, 5—5, in Fig. 1, certain cam parts of Fig. 2 being omitted;

Fig. 6 is an enlarged perspective view of one of the seaming units embodied in the head, with parts broken away; and

Fig. 7 is a vertical section of the seaming unit shown in Fig. 6.

2

As a preferred and exemplary embodiment of the invention the drawings illustrate a high speed rotary type seaming head having first and second operation seaming units A including seaming rollers B which revolve around a stationary sheet metal can C (Fig. 1) and a superimposed cover D to effect an interfolding of flange parts of the can and the cover for uniting these parts in an end seam such as, for example, the well known double seam used in the can making industry. The seaming operation preferably is performed with the can C and its superimposed cover D clamped between a can lifter plate or support 21 and a chuck 22 which forms a part of the head.

The can support 21 preferably is formed on the upper end of a vertically movable stem 23 slideably disposed in a bearing bracket 24 which projects outwardly from a machine frame 25 which may constitute the main frame of a more elaborate machine in which the seaming head is used. The stem 23 may be raised and lowered in any suitable manner to clamp the can and its cover against the chuck.

The chuck 22 (Figs. 1, 5 and 6) is stationary and in the case shown in the drawings is rectangular in contour with rounded corners for a can C of rectangular shape although the invention is equally well adapted to oval cans and cans of other irregular shape. The chuck 22 is bolted to a flange 28 formed on the lower end of a vertically disposed stationary chuck sleeve 29 which at its upper end is clamped tightly in a split bearing 31 formed in the upper portion of the machine frame 25. An adjusting nut 32 is threadedly engaged with the upper end of the sleeve 29 to provide for vertically adjusting the chuck 22. After an adjustment, the nut is clamped against rotary and vertical movement by a clamp ring 33 secured by screws to the bearing 31.

The bottom of the chuck 22 is recessed for a conventional knockout pad 35 for ejecting a seamed can and its cover from the chuck after the seaming operation. This knockout pad 35 is secured to the lower end of a rod 36 which extends up through the chuck sleeve 29. The rod projects above the sleeve and is actuated by cam action in the usual manner.

The seaming units A which carry the seaming rollers B around the stationary can C are located in a rotatable, cylindrical head housing 41 (Figs. 1, 3, 4 and 6) which is mounted on and keyed to the lower end of a head sleeve 42 (Figs. 1 and 4) which surrounds and which is rotatably mounted on the chuck sleeve 29. A nut 43 threadedly secured to the lower end of the head sleeve 42

holds the head 41 in place on the sleeve. The head sleeve extends upwardly along the chuck sleeve and at its upper end is formed with a hub 44. This hub is mounted on a roller thrust bearing 45 (Fig. 1) carried on a bushing 46 threadedly secured to the chuck sleeve 29 and held in place by a lock nut 47.

The head housing 41 is rotated continuously by a gear 51 which is formed on the hub 44 (Fig. 1) and which meshes with and is driven by a driving gear 52. The driving gear 52 may be a part of the mechanism of the seaming machine in which the seaming head is mounted and this gear 52 may be driven in the usual manner.

There are four seaming units A carried in the head housing 41 and they are equally spaced around its interior periphery. These units are all identical in construction and operation. Two of the units, disposed diametrically opposite, are first operation units and carry first operation seaming rollers 55 (Fig. 5) and the other two, also diametrically disposed, are second operation units and carry second operation seaming rollers 56.

Each seaming unit A includes a vertically disposed rocker shaft 61 (Figs. 1 and 7) which adjacent its lower end carries a ball bearing 62 (see also Fig. 6) mounted in a retaining bore or collar 63 in the head housing 41. Below the ball bearing, the rocker shaft is reduced in diameter and carries a seaming roller arm 65. It is on the outer ends of these arms that the seaming rollers B (55, 56) are rotatably mounted. The rollers are disposed in a horizontal plane with the chuck 22 and the flange parts of the can C and its cover D for rolling action against these flange parts as will be hereinafter explained.

Above the ball bearing 62, the rocker shaft 61 is rotatably mounted within a rocker sleeve 67 which is rotatably carried in a bearing 68 which projects inwardly from the inner surface of the head housing 41 (Fig. 6). Above the rocker sleeve 67, the rocker shaft 61 carries a rocker gear 69 which is keyed to the shaft and which is held in place by a screw 71 threadedly secured in the upper end of the shaft. The gear 69 and the shaft 61 and the seaming roller arm 65 thus are rotatable as a unit.

The rocker sleeve 67, immediately below its bearing 68 carries a seaming lever 73 which is clamped around the sleeve and which extends in a horizontal direction opposite to that of the seaming roller arm 65 and at a slight angle thereto (see Fig. 6). This seaming lever 73 at its outer end carries a seaming cam roller 74 (see also Fig. 3). There is one of these cam rollers for each seaming unit A. The two cam rollers on the first operation seaming units are disposed at a higher level than those of the two rollers on the second operation seaming units, and operate against a rotatable first operation edge cam 76 (Figs. 1, 2, 3, and 6).

The lower level rollers of the second operation seaming units operate against a second operation edge cam 77 which is integral with the first operation edge cam 76 and which rotates therewith (Figs. 1 and 3). These cams operate at the proper time to move the seaming rollers B into and out of seaming engagement with the can and cover flange parts to effect the seaming operation as will be hereinafter explained. The rollers are pressed against the cams 76, 77 by spring barrels 78 (Fig. 3) carried in sockets 79 threadedly secured in the head housing 41. The spring barrels

engage against the seaming levers 73 as shown in Fig. 3.

Rotation of the seaming edge cams 76, 77 is effected by a cam sleeve 81 on the lower end of which the cams are secured (Figs. 1 and 3). This sleeve is rotatably mounted on the head sleeve 42 and is also journaled in a long stationary bearing 82, clamped at its upper end in the machine frame 25 (see Fig. 1). Above the bearing 82, the cam sleeve 81 is formed with a gear 83 which meshes with and is driven by a gear 84, which like the gear 52 may be a part of the mechanism of the seaming machine in which the seaming head is mounted. The gear 84 is driven in unison with the gear 52 and is slightly larger in diameter than the gear 52 for rotating the gear 83 slightly faster than the gear 51. This is a conventional differential gear arrangement which is common in seaming heads used in the can making industry.

Movement of the seaming rollers B into and out of seaming engagement with the can and cover flange parts to effect the seaming operation is brought about through a rocker arm 87 (Figs. 2, 6 and 7) which is formed on the rocker sleeve 67 and which extends outwardly in the general direction of the seaming lever 73. There is one of these rocker arms 87 for each rocker sleeve. These rocker arms at their outer ends carry a vertical stationary pin 88 on which a follower or contour gear 89 is freely mounted.

The gear 89 of each seaming unit A meshes with the gear 69 keyed to the rocker shaft 61. Each of the gears 89 are also secured to a follower or contour arm 91 which extends back over the tops of the gears 69, 89 and at its free end carries a cam roller 92. There is one follower arm 91 and one cam roller 92 for each seaming unit A. The cam rollers operate in a cam groove 94 of a stationary contour cam 95 bolted to a flange 96 of the stationary bearing 82. The contour cam groove 94 is designed to provide for the seaming rollers B, a path of travel around the can C and its cover D, identical in contour to that of the shape of the can and cover.

Hence as the head housing 41 rotates and revolves the seaming units A around the stationary can C and its superimposed cover D, the follower cam rollers 92 traverse the stationary cam groove 94. During this travel of the cam rollers 92, the cam rocks the follower arms 91 and the attached follower gears 89 in accordance with the shape of the cam groove and this rocks the meshing rocker gears 69 and their attached rocker shafts 61. This rocking of the shafts 61 swings the attached seaming roller arms 65 in the opposite direction to that of the follower arms 91. Hence when the follower arms 91 move outwardly, the seaming roller arms 65 move inwardly and in like manner when the follower arms move inwardly, the seaming roller arms move outwardly. In this manner the seaming rollers B on the arms 65 are made to follow the exact contour of the chuck 22 and the can and cover flange parts carried thereon while the seaming rollers move around the chuck in spaced relation thereto.

Since the follower cam 95 is disposed above the head housing 41 it may be made in dimensions of a size large enough to insure extremely accurate operation. Being above the head housing 70 it is not restricted by the size of the housing and therefore the housing may be small enough to permit of considerable saving in its over-all diameter. Thus the head may be rotated at higher speeds with a resultant increase in production.

Movement of the seaming rollers B inwardly toward the can and cover flange parts to effect the seaming operation as the rollers follow the contour of the chuck 22, as effected by the seaming cams 76, 77 and cam rollers 74 on the seaming levers 73, rocks the sleeves 67 on the rocker shafts 61 and thus swings the rocker arms 87 outwardly. This shifts the pins 88 on which the follower gears 89 are mounted and thus pivots the contour arms 91 on their cam rollers 92 operating in the stationary cam groove 94. This pivoting of the contour arms has the effect of partially rotating the follower gears 89 and their meshing rocker gears 69 in a direction which swings the seaming roller arms 65 inwardly toward the chuck 22. In like manner, when the seaming operation is completed the seaming cams 76, 77 swing the rocker arms 87 inwardly and thus rotates the gears 69 and 89 in a direction which moves the seaming roller arms 65 away from the chuck 22.

It should be understood that in effecting this seaming operation, the first operation seaming rollers 55 are first moved into engagement with the can and cover flange parts on the chuck 22 to effect the first operation of the seam as is customary in such double seaming operations and upon completion of this first operation these rollers are shifted away from the partially formed seam and the second operation rollers 56 are moved into engagement with the seam parts to complete the seam.

In such a construction of seaming head there is only one rocker shaft 61 for each seaming unit A. The seaming roller B is attached to this rocker shaft and the shaft is rocked, through the gears 68, 89 for the dual purpose of guiding the seaming roller around the chuck 22 and its held can and cover in an orbit parallel to the contour of the chuck and of shifting the seaming roller into and out of seaming position. Thus the entire movement of the seaming roller is effected through rotation of the rocker shaft. This greatly simplifies the construction of the head and provides for greater accuracy and economy in the formation of the end seam.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a seaming head for uniting either circular or non-circular can ends to cans, the combination of a chuck having a shape corresponding to a can and an end to be seamed, a head housing having rotative movement around said chuck, a rocker shaft mounted in said head housing, a seaming roller carried by said rocker shaft adjacent said chuck, means including a stationary cam for rocking said rocker shaft during rotation of said housing to guide said seaming roller around said chuck in an orbit parallel to the contour of the chuck, said means also including a rocker arm mounted for rotation on said rocker shaft, means for oscillating said rocker arm on said rocker shaft, and means for transferring the oscillating movement of said rocker arm to said rocker shaft to modify the said orbit movement of said seaming roller to shift said roller into and out of seaming position.

2. In a seaming head for uniting either circular

or non-circular can ends to cans, the combination of a chuck having a shape corresponding to a can and an end to be seamed, a head housing having rotative movement around said chuck, a rocker shaft mounted in said head housing, an arm secured to said rocker shaft and carrying a seaming roller adjacent said chuck, a stationary cam patterned on the shape of said chuck, connecting means disposed between said stationary cam and said rocker shaft for guiding said seaming roller around said chuck in an orbit parallel to the contour of the chuck during rotation of said housing, said connecting means including a rocker arm mounted for rotation on said rocker shaft, means for oscillating said rocker arm on said rocker shaft, and means operating through said connecting means for transferring the oscillating movement of said rocker arm to said rocker shaft to modify the said orbit movement of said seaming roller thereby shifting said roller into and out of seaming position.

3. In a seaming head for uniting can ends to cans, the combination of a non-circular chuck for holding a can having a non-circular end to be seamed, a head housing having rotative movement around said chuck, a rocker shaft mounted in said head housing, a seaming roller arm secured to said rocker shaft and carrying a seaming roller adjacent said chuck, a gear also secured to said rocker shaft, means including a contour cam and interconnecting movable parts operating through said gear for oscillating said rocker shaft to guide said seaming roller around said chuck in an orbit parallel to the contour of the chuck, and means including a cam and interconnecting parts operable through said gear and also through some of said contour cam movable parts for oscillating said rocker shaft to modify its orbit movement to shift said seaming roller into and out of seaming position.

4. In a seaming head for uniting can ends to cans, the combination of a stationary chuck for holding a can having a non-circular end to be seamed, a head housing having rotative movement around said chuck, a rocker shaft rotatably mounted in and carried by said head housing, a seaming roller arm secured to one end of said rocker shaft and carrying a seaming roller adjacent said chuck, a gear secured to the other end of said rocker shaft, follower means including a follower gear engaging with said rocker shaft gear, said follower gear having rotation on a normally stationary pin, means including a stationary cam for actuating said follower means to oscillate said follower gear on its pin and through said rocker shaft gear to oscillate said rocker shaft for guiding said seaming roller around said chuck in an orbit parallel to the contour of the chuck during rotation of said head housing, and means mounted in part on said rocker shaft and having connection with said follower gear for moving its pin and through said gears for rocking said rocker shaft to shift said seaming roller into and out of seaming position.

5. In a seaming head for uniting can ends to cans, the combination of a stationary chuck for holding a can having a non-circular end to be seamed, a head housing having rotative movement around said chuck, a rocker shaft rotatably mounted in said head housing and carried thereby around said chuck, a seaming roller arm secured on one end of said rocker shaft, said arm carrying a seaming roller adjacent said chuck, a gear secured to the other end of said rocker shaft, a rocker sleeve rotatably mounted on said rocker

shaft intermediate said rocker shaft gear and said roller arm, and providing a support element, a follower arm pivotally mounted on said support element, said follower arm having geared connection with said rocker shaft gear, cam means operable on said follower arm and through said geared connection with said rocker shaft gear to oscillate said rocker shaft for guiding said seaming roller around said chuck in an orbit parallel to the contour of the chuck, and means operable on said rocker sleeve and through said support element and gear connections with said rocker shaft for shifting said seaming roller into and out of seaming position.

6. In a seaming head for uniting can ends to cans, the combination of a stationary non-circular chuck for holding a can having a non-circular end to be seamed, a head housing having rotative movement around said chuck, a rocker shaft rotatably mounted in and carried by said head housing, a seaming roller arm secured to said rocker shaft, said arm carrying a seaming roller disposed adjacent said chuck, a rocker gear also secured to said rocker shaft, a rocker sleeve rotatably mounted on said rocker shaft, said sleeve projecting laterally in a rocker arm, a pin mounted on and carried by said rocker arm, a follower gear rotatably mounted on said pin for meshing with said rocker gear, a follower arm secured to said follower gear, a cam roller mounted on the end of said follower arm, a stationary contour cam having a cam track corre-

10 sponding to the non-circular contour of said chuck said cam track being traversed by said cam roller during rotation of said head housing for rocking said follower gear and its meshing rocker gear to rotate said rocker shaft on its axis thereby guiding said seaming roller in an orbit surrounding and parallel to the contour of the chuck, a lever secured to said rocker sleeve, said lever carrying a seaming cam roller, a rotatable seaming cam operable on said seaming cam roller for independently rocking said follower gear and its meshing rocker gear to move said rocker shaft and shift said moving seaming roller into and out of seaming position.
